(57) **CLAIM**

The ornamental design for a messenger bag, as shown and described.

DESCRIPTION

FIG. 1 is a top front perspective view of a messenger bag showing the claimed design;

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof;

FIG. 8 is a top front perspective view of the messenger bag with a strap; and,

FIG. 9 is a front view of the messenger bag with a strap. The broken lines in the figures show portions of the messenger bag that form no part of the claimed design.
